UNITED STATES PATENT OFFICE.

FRED E. WHITE, OF GARDNER, MASSACHUSETTS.

TANK FOR OIL-STOVES.

1,184,601.

Specification of Letters Patent. Patented May 23, 1916.

Application filed October 30, 1915. Serial No. 53,860.

To all whom it may concern:

Be it known that I, FRED E. WHITE, citizen of the United States, residing at Gardner, Massachusetts, have invented certain 5 new and useful Improvements in Tanks for Oil-Stoves, of which the following is a specification.

This invention relates to liquid holding tanks and consists in providing a glass insert for the end of oil tanks forming the fuel reservoir of oil stoves although its use is not limited in this respect. The oil tanks of this type are removable from the stove and the filling orifice is usually at the bottom so that when the tank is removed from the stove the tank is inverted and filled with oil in this position and then reversed as the tank is applied to the stove, operating on the usual student lamp principle.

20 In an application filed November 12, 1914, #871761, I have shown a glass insert for a reservoir but this is concentrically arranged relative to the end of the tank, and in my present improvement I arrange it eccentric, 25 with the lower edge of the glass in normal position as near as practicable the bottom of the tank. This permits accurate observation of the lowering contents of the tank when in use and when the tank is being filled 30 the port allows, in the eccentric position of the glass, full observation of the rising oil

and enables the tank to be filled to the utmost without overflowing the same.

In the drawing, Figure 1 is a perspective view of an ordinary form of tank containing 35 my improvement, while Fig. 2 is an end view.

In the drawing the numeral 1 indicates the tank, 2 the end piece of the same, and 3 the glass insert carried by the end piece. 40

As I have above explained, I arrange the glass port eccentrically of the end of the tank in order that accurate observation may be made of the contents whether in the normal position shown as the oil is feeding or whether 45 in inverted position when the tank is being filled. By this means the tank can be used until every drop of oil has issued therefrom and in filling the height of the oil can be observed so as to completely fill the tank 50 without danger of overflow.

What I claim is:

A liquid holding tank for oil stoves having a feeding orifice at its bottom and adapted to be filled through the same orifice when 55 the tank is inverted, a glass insert or port for the tank arranged eccentrically at the end thereof and nearer the bottom than the top, substantially as described.

In testimony whereof I affix my signature. 60

FRED E. WHITE.
